UNITED STATES PATENT OFFICE.

WILLIAM E. LINDSLEY, OF BROOKLYN, NEW YORK.

ELECTRICAL CONNECTER.

Application filed February 15, 1927. Serial No. 168,344.

The present invention is concerned with the provision of means for effecting a good and secure electrical connection between a pair of wires.

5 The invention is particularly concerned with the twisting together of a pair of electrical conductors in such a manner that a good electrical contact is established between them, and the connected twisted portions of the wires are entirely protected and concealed.

A further object is to provide means for making an electrical connection of this kind in such a manner that there is no danger of 15 the wires becoming untwisted, and no danger of fouling the contact thus made, even though the connector be located in an exposed position where it is subjected to the action of rain and snow.

20 Other objects of the invention are to provide an electrical connecting device by which two wires may be connected together with expedition and facility, and a connecting device of simple, practical construction 25 which will be rugged, durable and efficient in use, and well suited to the requirements of economical manufacture.

With the above noted and other objects in view, the invention consists in certain 30 novel features of construction and combinations and arrangements of parts, as will be more fully hereinafter set forth and pointed out in the claims. The invention may be more fully understood from the following 35 description in connection with the accompanying drawings, wherein—

Fig. 1 is a longitudinal sectional view through a double electrical connector embodying the present invention.

40 Fig. 2 is an end view thereof with parts broken away and in section for the sake of clearness.

It is to be understood at the outset that the electrical connectors of the present invention may be made as individual units, or may be in the nature of a multiplicity of units rigidly or integrally connected together. For the sake of illustration I have shown a double unit connector consisting of 45 a single block 10 of insulating material having two sockets 11 therein coacting with two plugs 11^a which screw into the sockets. Each socket plug and associated mechanism consists of a complete electrical connector 50 unit, and the block 10 might be provided with a single socket or with any number of

sockets for the reception of associated plugs in accordance with the particular use to which the connector is to be put, and the particular number of wires to be connected. 60

Each of the sockets 11 includes an outer threaded portion 12 and an inner, preferably unthreaded chamber portion 12^a within which the two wires to be connected, designated at 13 and 14 are twisted together. 65

A restricted bore 15 extends from the bottom of the socket 11 through a nipple 16 integral with the end of the block 10. The bore 15 is enlarged and shouldered at 17 for the reception of insulation 18 of the wire 14, 70 the wire from the shoulder on being stripped. The wire 14 is inserted through the nipple 16 until the insulation 18 abuts the shoulder 17, the stripped end of the wire extending through and beyond the socket 11. 75 The wire as it is inserted through the bore 15 is passed through a cap 19 which is subsequently screwed on to the threaded nipple 16 and clamps a rubber gasket 20 against the outer face of the nipple to seal the connector 80 against any leakage through the passageway 15 and incidentally to retain the wire 14 against retractive movement.

The plug 11^a is formed with a reduced threaded extension 21 adapted to be screwed 85 into the threaded portion 12 of the socket 11. The shoulder defined by the threaded extension 21 may be faced with any suitable material at 22 to provide a wear surface 90 which engages the end face 23 of the block 10 when the plug 11^a is screwed home. The plug is formed with a longitudinally extending socket 24 having a flared mouth 25 for the reception of the end of the wire 14 which projects out of the socket 11. The 95 plug is also formed with a shouldered bore 26 corresponding with the bore 15 and with a nipple 27 and cap 28 for retaining and sealing the wire 13 which is introduced through the bore 26 and adapted to enter an aligned reduced socket 29 communicating with the socket 11 and having a flaring mouth 30 to guide the end of the wire 13 into place.

The upper connector unit of Fig. 1 has 105 been shown disassembled with the two wires 13 and 14 secured in the plug 11^a and the block 10 respectively. It will be seen that as the plug is advanced toward the block, the ends of the wire 14 and 13 will enter 110 their respective sockets 24 and 29 before the reduced extension 21 reaches the threaded

portion 12 of the socket 11. Passageway 15 and its aligned socket 24, and passageway 26 and its aligned socket 29 are arranged on opposite sides of the aligned central longitudinal axis of the socket 11 and the plug extension 21 which screws into the socket. Thus, when the plug is screwed home, the ends of the wires 13 and 14 will be twisted together in the inner unthreaded chamber 10 portion 12^a of the socket 11. The lower connector unit of Fig. 1, has been shown with the plug screwed completely home, and the twist formed in the wire.

Screwing home of the plug may to a certain extent tend to withdraw the ends of the wire 13 and 14 from their respective sockets 29 and 24, but such retractive tendency will be slight since it will be remembered that the extension 21 is continuously shortening the distance between bores 15, 26 and cooperating sockets 24, 29 as it is screwed home.

Preferably some means is provided for retaining the plug 11^a against accidental retrograde turning movement after the twist has been made in the wire by screwing the plug home. This means has been illustrated as a spring pawl 35 secured to the block 10 and cooperating with ratchet teeth 36 on the periphery of the plug 11^a.

With the plug screwed home and held against retrograde movement by the ratchet and pawl mechanism, there is no danger of the wire ends becoming accidentally untwisted, and there is no danger of moisture entering the connector and effecting the twisted connection due to the presence of the sealing caps 19, 28 and the presence of the wear plate 22 which may also be in the nature of a sealing device.

The blocks 10 may be molded, cast, or machined of any desired insulating material, and the blocks may be made in single or multiple units as will be readily understood.

The particular unit illustrated is a double unit, but even with half of the block 10 cut away there will be provided an electrical connecting device constructed in accordance with the invention.

Obviously, various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

- An electrical connector including a body having a socket therein, the mouth of which is threaded, said body having a passageway therein through which a wire is adapted to be inserted with its end extending through and beyond the socket, a plug

member adapted to be screwed into the threaded mouth of the socket and having a passageway therein through which a second wire is adapted to be passed into the socket, means associated with said plug for slidably receiving the end of the wire passed through the body, and means associated with the body for slidably receiving the end of the wire passed through the plug, said passageways being disposed laterally of the common longitudinal axes of the plug and socket, whereby screwing the plug home effects twisting of the two ends of wire together within the inner end of the socket.

2. An electrical connector including a body having a socket therein, the mouth of which is threaded, said body having a passageway therein through which a wire is adapted to be inserted with its end extending through and beyond the socket, a plug member adapted to be screwed into the threaded mouth of the socket and having a passageway therein through which a second wire is adapted to be passed into the socket, means associated with said plug for slidably receiving the end of the wire passed through the body, and means associated with the body for slidably receiving the end of the wire passed through the plug, said passageways being disposed laterally of the common longitudinal axes of the plug and socket, whereby screwing the plug home effects twisting of the two ends of wire together within the inner end of the socket, the means for slidably receiving the wire ends comprising pockets in the body and plug adapted to be aligned with the wire passageways before the plug is screwed home.

3. An electrical connector including a body having a socket therein, the mouth of which is threaded, said body having a passageway therein through which a wire is adapted to be inserted with its end extending through and beyond the socket, a plug member adapted to be screwed into the threaded mouth of the socket and having a passageway therein through which a second wire is adapted to be passed into the socket, means associated with said plug for slidably receiving the end of the wire passed through the body, and means associated with the body for slidably receiving the end of the wire passed through the plug, said passageways being disposed laterally of the common longitudinal axes of the plug and socket, whereby screwing the plug home effects twisting of the two ends of wire together within the inner end of the socket, and means for preventing accidental unscrewing of the plug.

4. A device as described in claim 3, and wherein said last mentioned means comprises ratchet teeth on the plug and a coacting pawl carried by the body.

5. A device set forth in claim 1, and

wherein the plug carries a sealing ring engaging the face of the body to prevent leakage into the socket between the plug and body.

5 6. A device as set forth in claim 1, and wherein means associated with the outer ends of the passageways seals the wires and prevents leakage into the socket through the passageways.

10 7. An electrical connector including a body having a socket therein, the mouth of which is threaded, said body having a passageway therein through which a wire is adapted to be inserted with its end extending through and beyond the socket, a plug member adapted to be screwed into the threaded mouth of the socket and having a passageway therein through which a second wire is adapted to be passed into the socket, means associated with said plug for slidably receiving the end of the wire passed through the body, and means associated with the body for slidably receiving the end of the wire passed through the plug,

said passageways being disposed laterally of 25 the common longitudinal axes of the plug and socket, whereby screwing the plug home effects twisting of the two ends of wire together within the inner end of the socket, the means for slidably receiving the 30 wire ends comprising pockets in the body and plug adapted to be aligned with the wire passageways before the plug is screwed home, said pockets having flaring wire guiding mouths.

15 8. An electrical connector including a pair of connected members relatively rotatable about a common axis and cooperatively defining a chamber between them, each of said members having a pair of wire receiving 40 passageways therein adapted to be aligned with the corresponding passageways of the opposite member, whereby when the ends of two wires have been passed through the aligned passageways, relative rotation of 45 the members will effect twisting of the wires together in the chamber.

WILLIAM E. LINDSLEY.
